DISTRIBUTOR GOVERNOR SHAFT ASSEMBLY

Eugene C. Bettini, Birmingham, Mich., assignor to Holley Carburetor Company, Van Dyke, Mich., a corporation of Michigan

Application June 13, 1956, Serial No. 591,168

6 Claims. (Cl. 121—43)

The present invention relates to a distributor governor shaft assembly.

It is an object of the present invention to provide a rotatable shaft construction which forms two separate passages along the length of the rotating shaft so that two variable pressure sources may be connected to separate operating devices.

More specifically, it is an object of the present invention to provide a shaft as described, formed of two sections which may be readily machined and assembled together to provide the plurality of passages referred to.

It is a feature of the present invention to provide a first shaft section having a fluid passage extending axially into one end thereof, a second shaft section having a recess in which the end portion of the first shaft section is received, said recess affording a fluid passage extending along the side of the end portion of the first shaft section, a transverse opening extending through overlapped portions of said first and second shaft sections and communicating with the passage in said first shaft section, and a tube located in and closing said transverse opening, said tube having a port in the side thereof registering with the passage in said first shaft section at the side of the tube remote from the end of said first shaft section.

Other objects and features of the invention will become apparent as the description proceeds, especially when taken in conjunction with the accompanying drawing, wherein:

Figure 1 is a fragmentary sectional view through a distributor having a governor control valve therein, showing the governor valve.

Figure 2 is a fragmentary sectional view similar to Figure 1 showing the distributor adjusting mechanism.

Figure 3 is an enlarged sectional view of the shaft assembly.

Figure 4 is a section on the line 4—4, Figure 3.

The shaft assembly which forms the subject matter of the present invention is indicated at 10 and is adapted to be geared or otherwise connected to the cam shaft of an internal combustion engine. In Figure 1 the shaft 10 is diagrammatically illustrated as connected by gearing 10a to an engine cam shaft 10b. The upper end of the shaft 10 is received in the distributor housing 12 and is connected to the usual distributor arm indicated at 14. Carried by the upper end of the shaft 10 for rotation therewith and for small angular adjustment relative thereto is cam mechanism indicated generally at 16 adapted to operate the breaker indicated generally at 18.

Angular adjustment of the cam 16 relative to the shaft 10 is effected by means responsive jointly to engine speed, as indicated by centrifugal force developed in fly weights 20 and manifold vacuum as effective on flexible diaphragm means indicated at 22. Details of this mechanism forms no part of the present invention and are referred to merely to explain the necessity for passage means indicated at 24 in this figure, which is separate and distinct from other passage means also extending longitudinally of the shaft 10. The portion of the pas-

2

sage shown at 24 communicates by means subsequently to be described, with a fitting 25 which may connect to a source of manifold vacuum.

Governor means for limiting the speed of the vehicle controlled thereby may be provided in the form of a fluid motor connected to the engine throttle valve and adapted to be operated by a differential pressure source, such for example as carburetor vacuum. In accordance with the present invention the fluid motor has passage means including a connection or fitting 26 controlled by a bleed valve including ports 28 which are adapted to be closed by a fly weight 30 when the engine attains sufficient speed to cause the centrifugal force of the fly weight to overcome the adjustable spring 32. It will be observed that the ports 28 communicate with a passage 34 extending longitudinally of the transfer tube or shaft 36 the outer end of which is closed by a plug 38. Weight 30 is tubular, and slides on tube 36 under centrifugal forces opposed by spring 32 to overlie and close ports 28.

Referring now to Figures 3 and 4 it will be observed that the shaft assembly indicated generally at 10 comprises a first shaft section 40 having an end portion reduced as indicated at 42 to provide a seat for the end portion 44 of the second shaft section 46. Beyond the reduced portion 42, the first shaft section 40 is further reduced as indicated at 48. Beyond the reduced portion 48 the end of the shaft section is again enlarged as indicated at 50. Extending along one side, the enlargement 50 is cut away to provide the passage forming relief or flat surface indicated at 52. Extending into the end of the first shaft section 40 is a centrally located axially extending passage 54 and this communicates with a lateral passage 56 which in turn extends to the side of the first shaft section 40.

The second shaft section 46 is provided with a relatively deep elongated recess 58 of circular cross-section, the bottom of the recess as indicated at 60 being of slightly smaller diameter to snugly receive the enlargement 50 at the end of the first shaft section 40. Adjacent the lower end of the second shaft section, as seen in Figure 3, there is provided a transverse passage 62 extending to the side of the second shaft section. It will be observed that the bottom of the recess 58 is tapered as indicated at 64, thus leaving a small chamber at the end of the first shaft section. Extending axially beyond the bottom of the recess 58 is a second fluid passage 66 which in turn communicates with a transversely extending opening 68.

It will be observed that the various passages and reduced and enlarged portions so far described may be formed efficiently and economically when the shaft sections 40 and 46 are separated. Thereafter, the parts are assembled together in the position shown and brazed, as for example at 70 and 72. With the parts brazed in the position shown in Figure 3, a through transverse opening 74 may be drilled communicating with the elongated fluid passage 54. The opening 74, as best seen in Figure 1, is adapted to be closed by the tubular transfer shaft 36 which serves to separate the portion of the fluid passage 54 therebelow from the fluid passage 66. It will be observed that the tubular shaft 36 includes a port 76. With the parts as just described, it will be observed that the transverse passage 56 communicates with the axially extending fluid passage 54 which in turn communicates with the interior of the tubular shaft 36 through the port 76. At the same time the transverse passage 62 communicates with an annular chamber formed by the reduced portion 48 of the shaft section 40 within the recess 58, thence through the passage formed by the flattened portion 52 into the chamber between the end of the first shaft section and the tapered wall 64, and thence through

the passage 66 into the transverse opening 68, which includes a ported tube 89 as seen in Figure 2.

Referring again to Figure 1, it will be observed that the transverse passage 56 is in constant communication during shaft rotation with an annular chamber 82 connected by the inclined passage 84 with the fitting 26. In like manner, the transverse passage 62 is in constant communication during rotation of the shaft with the annular chamber 86 which communicates through inclined passage 88 with the fitting 25.

The drawings and the foregoing specification constitute a description of the improved distributor governor shaft assembly in such full, clear, concise and exact terms as to enable any person skilled in the art to practice the invention, the scope of which is indicated by the appended claims.

What I claim as my invention is:

1. In an engine distributor governor valve assembly, a shaft adapted to be connected to a rotating part of an engine, distributor adjusting mechanism including a fluid motor connected to said shaft, a bleed valve for controlling governor operation connected to said shaft, said shaft being constructed to connect said fluid motor and bleed valve to separate variable pressure sources, said shaft comprising a first shaft section having a passage extending axially from one end thereof and a lateral passage extending to the side of said first shaft section at a point spaced from the end thereof, a second shaft section having a recess extending into one end in which the end portion of said first shaft section extends, a passage extending axially beyond the end of said recess and in communication therewith, said recess being spaced from the end portion of said first shaft section to define a fluid passage therebetween, a passage extending laterally between said fluid passage and the side of said second shaft section, a transverse passage intersecting said axially extending passage, a transverse tube receiving opening intersecting both said first and second shaft sections and intersecting the passage in said first shaft section, a tube in said opening closing said last named passage, and a port in said tube communicating with the said passage at the side thereof connected to said lateral passage.

2. A shaft assembly for connecting two fluid pressure devices carried thereby to different sources of fluid pressure, said shaft assembly comprising a first section having a first passage extending axially in one end portion from one end thereof, and a lateral passage connecting said first passage to a side of said first shaft section, a second shaft section having a recess extending into one end receiving the said end portion of said first shaft section, a second passage extending between the side of the end portion of said first shaft section received in said recess and the side of said recess from adjacent the end of said second shaft section to the bottom of said recess, a third passage extending axially from the bottom of said recess in said second shaft section, a first transverse opening extending through said second shaft section and intersecting said third passage, and a second transverse opening extending through both said first and second shaft sections and intersecting said first passage, and means blocking said first passage between the end of said first shaft section and said second transverse opening, comprising a tube extending through said second transverse opening, said tube having a port in the side thereof away from the said one end of said first shaft section.

3. Structure as defined in claim 2, said second passage being formed in part by a flattened end portion of said first shaft section, the recess in said second shaft section being of circular cross-section.

4. A shaft assembly comprising first and second shaft

sections permanently secured together, said second section having a deep circular recess in which an end portion of said first section is received, a passage between the side of the end portion of said first section and said recess communicating with the side of said second section and with the inner end of said recess, said recess having a reduced extension, a first transverse opening extending across said second section and communicating with said reduced extension, said first shaft section having an axially extending passage opening into the end thereof received in said recess, a second transverse opening extending across both said first and second sections and intersecting the passage in said first section, and means plugging the end portion of said last passage, comprising a tube in said second transverse opening, said tube having a port in the side thereof remote from the said end of said first shaft section.

5. A shaft assembly comprising a first shaft section having a first centrally disposed axially extending fluid passage opening into one end thereof, a second shaft section having a deep axially extending recess opening into one end thereof in which the said end of said first section is fitted, said second section having a second centrally disposed axially extending fluid passage communicating with the inner end of said recess, said recess and the portion of said first section received therein defining a third passage communicating with said second passage, a first transverse opening in said first and second sections intersecting said first passage, a second transverse opening in said second section intersecting said second passage, and a tube in said second opening having a port in the side thereof remote from the said end of said first section.

6. A shaft assembly for connecting two fluid pressure devices carried thereby to different sources of fluid pressure comprising a first shaft section having a first axially extending passage opening into one end thereof and a first lateral passage connecting said first passage to a side of said first shaft section, said first shaft section having an annular groove adjacent its said one end defining a radially enlarged head at the end thereof beyond said groove, said head having a passage forming relief extending axially of said shaft section completely across said head in predetermined angular position relative to said first lateral passage, a second shaft section having a deep axially extending recess opening into one end and receiving the aforesaid one end of said first section including all of said annular groove and defining therewith an annular chamber, a second lateral passage connecting said annular chamber with a side of said second shaft section, the passage forming relief on said head cooperating with the inner surface of said recess to define a third passage connecting said annular chamber to a portion of said recess beyond the said one end of said first shaft section, a first transverse opening extending through said head and said second shaft section and intersecting said first passage and spaced from said third passage, a second transverse opening extending through said second shaft section and communicating with said recess, and a tubular member in said first transverse opening having a port at the side thereof remote from the said one end of said first shaft section in communication with said first passage.
